United States Patent

Des. 234,315
Patented Feb. 11, 1975

234,315

PHONOGRAPH

Robert F. Mansfield, Tokyo, Japan, assignor to
Capehart Corporation, New York, N.Y.

Filed Sept. 18, 1972, Ser. No. 290,074

Term of patent 14 years

Int. Cl. D14—01

U.S. Cl. D56—4 R

FIG. 1

FIG. 2

FIG. 3

FIG. 4

FIG. 5

FIG. 1 is a front and top perspective view of a phonograph showing my new design;

FIG. 2 is a front elevational view;

FIG. 3 is a left side elevational view;

FIG. 4 is a top plan view; and

FIG. 5 is a bottom plan view.

The rear is plain and unornamented.

I claim:

The ornamental design for a phonograph, as shown and described.
